United States Patent Office

Des. 188,311
Patented July 5, 1960

188,311

BUILDING

Flynn E. Hudson, Jr., 145 Carter Road, Decatur, Ga.,
and La Fayette M. Sheffer, 1734 Moores Mile Road
NW., Atlanta, Ga.

Filed Oct. 16, 1957, Ser. No. 48,123

Term of patent 14 years

(Cl. D13—1)

Des. 188,311

We claim:

The ornamental design for a building, as shown.
